UNITED STATES PATENT OFFICE.

JOSEPH N. LAPOINTE, OF BOSTON, MASSACHUSETTS.

KEY-SEAT-BROACHING MACHINE.

No. 876,277.

Specification of Letters Patent.

Patented Jan. 7, 1908.

Application filed October 6, 1904. Serial No. 227,271.

To all whom it may concern:

Be it known that I, JOSEPH N. LAPOINTE, a citizen of the United States of America, and a resident of Boston, in the county of Suffolk and State of Massachusetts, have invented certain new and useful Improvements in Key-Seat-Broaching Machines, of which the following is a specification.

This invention relates to key seat broaching machines and has for its object the production of a machine in which key seats may be cut in pulleys, gears and similar articles having bores of different diameters, without requiring any complicated adjustments or change in the mechanism to adapt the same for the different sizes of bores in the articles to be operated upon.

It provides for a suitable mechanism for operating the working tool, insuring a steady movement during its operation, thereby accomplishing better results than in machines now in general use.

Provision is made for imparting to the cutting tool a slow motion during the forward or cutting portion of its stroke, and for automatically stopping said tool at a predetermined point, while the invention further provides for a rapid return of the tool into its normal position preparatory to another cutting.

It further consists in certain novel features of construction and arrangement of parts which will be readily understood by reference to the description of the drawings and to the claims to be hereinafter given.

Of the drawings: Figure 1 represents a plan of a machine embodying the features of this invention. Fig. 2 represents a rear side elevation of the same, showing the reducer partially cut in section and a gear to be operated upon mounted upon the arbor thereof. Fig. 3 represents a sectional elevation of the driving and reversing mechanisms. Fig. 4 represents a sectional elevation of the same parts, the cutting plane being on line 4—4 on Fig. 3. Fig. 5 represents an end view of the supporting plate, reducer and working tool. Fig. 6 represents a sectional elevation of the tool holder and reciprocating carriage, the cutting plane being on line 6—6 on Fig. 1. Fig. 7 represents a sectional elevation of the same, the cutting plane being on line 7—7 on Fig. 6, and Fig. 8 represents a detail of one of the adjustable stops.

Similar characters designate like parts

throughout the several figures of the drawings.

In the drawings, 10 represents a base provided with lateral projections 11 and 12. The projections 12 are provided with suitable bearings 13 for elongated bushings 14. The bushings 14 have an interior bore of the same diameter as the screw 15 slidable therein. The screw 15 has secured to its opposite end a carriage 16 provided with a T groove 17 in which is mounted a tool holder 18 having flanges 19 to fit the T groove 17. The shank 20 of the tool holder 18 is threaded and said threaded shank is provided with a clamping nut 21.

The tool holder 18 may be adjusted lengthwise of the T groove 17 into any desired position and clamped in said adjusted position by means of the clamping nut 21. The outer end of the shank 20 is forked and is adapted to receive the working tool, or cutter, 22 which is secured to said tool holder by means of the key 23 passing through said shank 20 and tool 22. The tool 22 is mounted in and moves freely in a groove 24 in a reducer 25 having a flanged cylindrical base fitting an opening in the supporting plate 26. The reducer 25 is provided with an arbor 26* adapted to fit a bore through any article in which it is desired to cut a key seat.

It is obvious that the supporting plate and the opening therein always remains the same and that it is necessary for each machine to have a plurality of reducers 25 provided with different sized arbors. The screw 15 has mounted thereon between the bushings 14 a nut 27, which, when revolved, operates upon said screw 15 to move the same endwise in the supporting bushings 14. These bushings serve as guides for said screw and cause it to move in a direct line without jar or tremor, the opposite end of said screw being mounted in the carriage 16 which has side grooves 28 into which is fitted the guide-ways 28* on the base 10 to further steady the screw while the same is being operated to draw the working tool 22 through the article being operated upon.

Each bushing 14 is provided with a collar 29 and a clamping nut 30 on either side of the bearings 13 to clamp said bushings in position to prevent endwise or other movement thereof. On one of these bushings is mounted a pulley 31. Loosely mounted upon the other bushing is a driving gear 32,

the gear 32 meshing with and being driven by a pinion 33 on a fixed shaft 34 about which said pinion is caused to revolve by means of the driving pulley 35 keyed thereto. 5 Keyed to and slideable upon the nut 27 is a grooved clutch member 36 provided with a conical flange 37 at one end, adapted to engage the conical hub 38 of the pulley 31 when said grooved clutch member 36 is moved by 10 the lever 39 pivoted at 40 toward said pulley 31.

The lever 39 is forked and provided with cylindrical projections 41 entering the groove 42 in said clutch member 36 and compelling 15 said clutch member to move in either direction when said lever 39 is moved about its pivot 40. The clutch member 36 is provided on the end opposite the conical flange 37 with projections 43 and the gear 32 has 20 pivoted thereto at 44 arms 45 which are held against stop pins 46 by the springs 47. The gear 32 is also provided with projections 48 in the path of said pivoted arms 45 and said arms 45 are in the path of the projections 25 43 on the sliding clutch member 36 when said clutch member has been moved into its extreme position toward said gear 32. When in this extreme position, the revolution of said gear 32 in the direction of the arrow 30 shown in Fig. 4, will cause the pivoted arms 45 to come into contact with the projections 43 and cause said clutch member 36 to commence to revolve in the same direction as the gear 32 is revolving. During this operation, 35 however, the spring 47 will gradually yield to permit the pivoted arms 45 to move over into contact with the projections 48 when the clutch member 36 and the gear 32 will move together positively until said clutch member 40 36 has been moved along the nut 27 to remove the projections 43 from the path of said pivoted arms 45. This clutch mechanism prevents any sudden shock in the operation of the machine. The outer end of the 45 lever 39 is connected by a link 49 to a lever 50 pivoted to a shaft 51 mounted in bearings in the base 10 and projecting through the rear thereof. To the rear end of the shaft 51 is keyed a lever 52 to the upper end of which 50 is pivoted a block 53 secured upon a rod 54 mounted in bearings 55 in which said rod is adapted to slide in a direction parallel with the operating screw 15.

The rod 54 is provided with a pin 55* with 55 which a forked lever 56 engages, said lever being keyed to a short shaft 57 passing through the projection 11 from the rear to the front of the machine and having keyed to the opposite end the operating handle 58 60 provided with an ordinary spring latch 59 engaging with the plate 60 to hold the rod 54 in its normal position, as shown in Fig. 2, with the clutch member 36 disengaged from either of the driving mechanisms. The rod 65 54 is provided at the end nearest the sup-

porting plate 26 with a stop 61 in the path of a rearwardly projecting arm 62 on the carriage 16 so that when the carriage 16 reaches its extreme outward position it will engage with said stop 61 and move the rod 54 to the right of Fig. 2, thereby operating the levers 52 and 39 to move the slideable clutch member 36 into its normal position intermediate the clutch members 31, 32.

In order to operate the machine, the parts 75 being in the position indicated in Figs. 1 and 2, the operator moves the handle 58 to the left thereby causing the clutch members 32—36 to engage and revolve the screw 15 in a direction to move the carriage 16 toward the driving mechanism which is so geared down that the screw will revolve very slowly to permit a more effective cutting. This movement of the working tool toward the driving mechanism will continue until the stop pin 85 63 in the projection 62 of the carriage 16 comes into contact with the adjustable stop 64 on said rod 54 when the rod 54 will be moved toward the driving mechanism and cause the slideable clutch member 36 to be 90 moved in a direction to disengage the clutches 32—36 and thus cause the rotation of the screw 15 to be stopped until by the operation of the handle 58 it is again moved in the opposite direction with its working 95 tool 22 into a position to commence a second operation.

In order to return the tool to its normal position preparatory to another cutting the handle 58 is moved to the right to engage the 100 clutch members 37—38, thereby causing the screw 15 to be rapidly rotated in the opposite direction to effect a quick return thereof, this movement causing the carriage 16 to be moved toward the holder 26 until the member 105 62 engages the arm 61 on the rod 54, causing a movement thereof to disengage the clutch members 37—38 and stop further rotation of said screw 15.

Should it be desired to stop the machine to 110 reverse the movement of the screw 15 before the carriage has reached the stop 61 the adjustable stop 66 flattened on one side may be moved about the rod 54 and clamped in any desired position so that the pin 63 in its 115 movement to the right (see Fig. 2) will engage with said stop 66 and stop the movement of the screw upon contact therewith.

The lower part of the base 10 is provided with a chamber for storing the extra reducers 120 and similar articles. The upper portion of the base 10 and projection 11 is hollowed out and provided with a bottom 67 inclining toward an opening 68 beneath which a receptacle may be placed to receive the chips and 125 oil passing down said inclined bottom and being ejected through said opening 68. The pulleys 31—35 are driven in the same direction by a belt from any suitable countershaft (not shown).

This mechanism produces a very effective machine for cutting key seats and slots in articles of various sizes and of different bores being simple in construction and very effective in operation.

By the use of a screw 15 to actuate the tool holder, a very steady movement is obtained for the cutter and as a consequence it is capable of performing much better work than can be done by cutters operated in the usual way, by a rack and pinion.

The driving mechanism for actuating the mechanism for reciprocating the tool holder is compact and simple, while it permits the reciprocation of the tool holder to be stopped in either direction without jar or injury, while it provides a rapid movement of the tool when not in operation and a slow movement when it is performing a cutting.

The ready means of securing the tool to the tool holder and the adjustability of the latter in the reciprocating carriage are other great advantages in this invention.

Having thus described my invention, I claim:

1. In a keyseat broaching machine, the combination of a tool holder; stationary bearings for said holder separated from each other; a driving member mounted upon each of said bearings; means interposed between said driving members for reciprocating said tool holder; and means for transmitting motion to said reciprocating means from either of said driving members.
2. In a keyseat broaching machine, the combination of a tool holder; stationary bearings for said holder separated from each other; a driving pulley mounted upon one of said bearings; a gear mounted upon a second bearing; means for driving said gear; means interposed between said gear and said driving pulley for reciprocating said tool holder; and means for transmitting motion to said reciprocating means from either said driving pulley or driving gear.
3. In a keyseat broaching machine, the combination of a tool holder; stationary bearings for said holder separated from each other; a driving pulley mounted upon one of said bearings; a gear mounted upon a second bearing; a pinion meshing with said gear; a driving pulley therefor; means interposed between said gear and said driving pulley for reciprocating said tool holder, and means for transmitting motion to said reciprocating means from either said driving pulley or driving gear.

4. In a keyseat broaching machine, the combination of a tool holder provided with a threaded portion; stationary bearings for said holder; a driving member mounted upon each of said bearings; a nut interposed between said bearings and engaging the threaded portion of said tool holder for reciprocating said tool holder; a slideable clutch member keyed thereto; and means for moving said clutch member to engage either of said driving members.

5. In a keyseat broaching machine, the combination of a tool holder; stationary bearings for said holder; a driving pulley mounted upon one of said bearings; a gear mounted upon a second bearing; means for driving said gear; a threaded tool holder in said bearings; a nut thereon interposed between said bearings for reciprocating said tool holder; a slideable clutch member keyed thereto; and means for moving said clutch member to engage either said driving pulley or driving gear.

6. In a keyseat broaching machine, the combination of a tool holder; bearings for said holder; a driving pulley mounted upon one of said bearings; a gear mounted upon a second bearing; a pinion meshing with said gear; a driving pulley therefor; a threaded tool holder in said bearings; a nut thereon interposed between said bearings for reciprocating said tool holder; a slideable clutch member keyed thereto; and means for transmitting motion to said clutch member from either said driving pulley or driving gear.

7. In a keyseat broaching machine, the combination of a tool holder; a non-revolving screw secured thereto; guides for said holder; a work support; cylindrical bearings fitting the periphery of said screw and in which it is adapted to reciprocate; a nut upon said screw between said bearings; a driving pulley mounted upon one of said bearings and provided with a tapered hub; a gear mounted upon the other; a radial key in said nut; a slideable member mounted upon said nut having a flange adapted for engagement with said hub; co-operating shoulders on said slideable member and said gear; and means for moving said slideable member lengthwise of said nut.

Signed by me at Boston, Massachusetts, this 3d day of October, 1904.

JOSEPH N. LAPOINTE.
